THOMAS HEWITT, OF BRIDGEPORT, CONNECTICUT.

KEYLESS PADLOCK.

1,316,037.

Specification of Letters Patent. Patented Sept. 16, 1919.

Application filed June 20, 1917. Serial No. 175,909.

To all whom it may concern:

Be it known that I, THOMAS HEWITT, a subject of the King of Great Britain, residing at Bridgeport, in the county of Fairfield 5 and State of Connecticut, have invented certain new and useful Improvements in Keyless Padlocks, of which the following is a specification.

This invention relates to padlocks, and 10 particularly to a permutation padlock that may be opened and closed by a person familiar with the combination but cannot be opened by those to whom the combination is unknown; furthermore, the lock is operable without the use of a key, is composed 15 of few parts, is of simple construction, strong and not liable to get out of order and therefore, is useful out-of-doors where it is exposed to the weather.

20 With the above and other objects in view the invention consists in the novel construction, combination and arrangement of parts hereinafter described, pointed out in the appended claims, and illustrated in the accompanying drawings in which:—

Figure 1, is an elevation of the lock with one side removed, showing the interior mechanism.

Fig. 2, is an elevation of one edge of the 30 padlock as seen from the left of Fig. 1, and

Fig. 3, is a horizontal sectional view on the line 3—3 of Fig. 1.

In the drawings 10 indicates the casing of the padlock which as shown may be made 35 of two similar parts, centrally divided and made of cast or pressed metal as desired. Each part 11 and 12 of the casing is provided at one side or edge with an opening 13 at the top of which opening is a depending curtain 14 having a narrow opening 15 therein for a purpose to be described later.

The two parts of the casing 10 are securely connected by rivets 16 and pivoted within the casing on a cross shaft 17 are three disks 45 18, 19 and 20, said disks being counterparts of each other and so positioned that a portion of their periphery projects through the opening 13 in position for convenient manipulation. Each disk has its peripheral edge 50 provided with a series of numbers as shown and a notch 21 formed at any point therein. Projecting from the periphery of each disk is a pin 22 seated in a recess, the positions of which may also be changed to prevent the 55 notches being alined by unauthorized per-

sons by providing a number of recesses in the periphery of each disk.

At the closed side of the lock case 10 is pivotally mounted an upright lever 23, the pivot 24 passing through its lower end to 60 connect the same to the case, while its upper end has on the rear side a notch 25, adapted to be engaged by a hook 26 on the end of a semi-circular shackle 27 pivoted at its other end at 28 between ears 29 projecting upwardly from the top of the two parts of the casing 10. A lug 30 projects from the side of the lever 23 toward the disks 18, 19 and 20 and is adapted to engage the notches 21 in said disks when they are in alinement and 65 opposite said lug. A spring 31 is mounted in the casing to bear against the lever 23 and press the same away from the disks so as to hold its upper end in engagement with the hook on the shackle 27. A push button 32 is seated in a sleeve 33 formed in the rear side of the casing 10 and is adapted to be moved longitudinally and press upon the lever 23 to swing the same toward the disks and disengage the upper end of said 70 shackle. To prevent said button 32 from being forced outwardly there is a head 34 formed on its inner end that bears against the inner end of the sleeve 33, when in its outermost position, and thus prevents the same from being lost.

The padlock as shown in Fig. 1 is locked and may be unlocked by rotating the disks until the numbers on the peripheries thereof as seen through the opening 15 form a combination which will indicate that the notches 21 in each disk are in alinement and opposite the lug 30 on the lever 23. Upon pressing the button 32, the lever will swing toward the disks, the lug 30 entering the notches therein and the hook 26 disengaged from the notch 25. The shackle 27 may then be raised. After the shackle has been again closed, its hooked end becomes engaged with the notch 25 in the lever 23 to 90 hold the shackle, the disks when turned will throw the notches 21 out of alinement, and until the numbers on their edges are seen through the window 15 in proper order, it will be impossible to open the padlock. It 100 will be seen that owing to the provision of the pins 22, complete rotation of the disks is prevented, and in this manner a person unfamiliar with the lock will be confused and preoccupied in attempting to strike the 105 110

combination by adjusting the disks with reference to their stopping points when limited by engagement of the pins with the lug 30 or a part of the casing. The pins 5 may furthermore be arranged at different points around the peripheries of the disk to confuse the person unfamiliar with the lock and who makes a second attempt to open the lock after an interval between his first 10 attempt.

I claim:

1. In a padlock, a casing having one end wall cut away, an extension of said wall forming a curtain, the same having an 15 observation opening, a plurality of disks mounted in the casing and having a segment thereof projecting through the opening of the casing whereby the peripheries of said disks are visible through the opening in the 20 curtain, a shackle, and means controllable by the disks for locking the shackle.
2. In a padlock, a casing having an open-

ing in one wall thereof, a plurality of disks each having a peripheral notch and being rotatably mounted in said casing, a radial 25 pin on each disk and projecting from the periphery thereof, a shackle, a pivoted locking bolt to engage the shackle, a lug on the bolt to enter the notches of the disk when the same are alined, said disks having a segment thereof projecting through said opening in the casing, said pins limiting the movement of the disks by engagement with the bolt lug or casing, resilient means to retain the bolt in locking position, and means 30 to urge the bolt toward an unlocking position.

In testimony whereof I affix my signature in presence of two witnesses.

THOMAS HEWITT.
